UNITED STATES PATENT OFFICE

ROBERT L. HIBBARD, OF BELLEVUE, PENNSYLVANIA

BENDING MACHINE

Application filed November 22, 1929. Serial No. 408,987.

The invention relates to machines for bending bars or rods into zig-zag forms primarily for use in making light trusses for floors and other structures. It has for its principal objects the provision of a machine of simple construction in which the labor required to operate is reduced to a minimum in proportion to the output of the machine; which will form the bends in the bars with uniformity and accuracy; and which will operate to make two bends in the stock at one time with no more manipulation or labor on the part of the operator in making the double bend than is required in making a single bend on the ordinary bending machine. One embodiment of the invention is illustrated in the accompanying drawings, wherein:

Figure 1 is a plan view of the machine with certain of the parts lying above the dies removed to show the parts beneath more clearly. Fig. 2 is a similar view with the bending dies in their other extreme of movement. Figs. 3 and 4 are elevations at opposite sides of the machine. Fig. 5 is a detail plan view of a part of the machine with the attachment applied for giving a sharp bend at the movable die. And Fig. 6 is an end elevation of the parts, as shown in Fig. 5.

Referring to the drawings, 1 is the base of the machine in which are mounted the vertical pivot rods 2 and 3, on which are pivoted the links 4 and 5. Pivots connected to the ends of the links by the pins 6 and 7 is the plate 8 which carries the movable die. This die consists of the members 9 and 10 with the slot 11 between them for receiving the bar 12 to be bent, the member 10 being provided with the bending toe 13 lying substantially over the center of the pin 6.

Lying so that its slot 14 is in alignment with the slot 11 is the fixed bending die made up of the members 15 and 16, the latter of which has a bending toe 17 lying substantially over the center of the pivot rod 2. The so-called fixed die, while held against movement in a horizontal direction, is mounted for a relatively small amount of vertical movement in order to free it from the bent bar after the bending operation, as later described. This is provided for by

mounting the die on the under side of a ribbed plate 18 pivoted upon the pin 19 supported in the lugs 20 projecting from the frame 1 (Figs. 2 and 3). The plate 18 is provided with a depending arm 21, which carries a second arm 22 pivoted thereto at 23. The arm 22 is clamped yieldingly against the arm 21 by means of a spring 24 surrounding the bolt 25 secured at its inner end to the arm 21. The arm 22 is provided at its end with a pin 26 engaging a cam 27 carried by the shaft 28. The rotation of the cam oscillates the arms 21 and 22 at timed intervals, thus raising the plate 18 and the fixed die at proper intervals. The use of the arm 22 and spring 24 gives a yielding operation for preventing breakage in case the movement of the plate 18 is positively interfered with, as sometimes occurs, when the bar which is being bent is not gotten out of the way when the plate is moved downward. The shaft 28 is driven from an electric motor 29 through the intermediary of the motor shaft 30, the bevel gears 31 and 32, cross shaft 33, worm 34 on the shaft 33, worm wheel 35 on the vertical shaft 36, bevel gears 37 and 38 on the shafts 36 and 39 respectively, and the bevel gears 40 and 41 on the shafts 39 and 28 respectively.

The link 4 is swung back and forth from the vertical shaft 36 by means of the crank 42 and connecting rod 43. The right hand end of the rod 43 is connected to the shoulder 44 (integral with the link 4) by means of the short link 45, such link being pivoted to the shoulder by means of the pin 46 and to the connecting rod by means of the pin 47. During the actuation of the link 4 from the rod 43, the link 45 oscillates back and forth; at one time occupying the position shown in engagement with the stop pin 48; and at another time occupying a position at approximately 90 degrees from the position shown in engagement with the stop pin 49 (Fig. 2). This provides for a pause in the movement of the link 4 when it reaches two extremes of oscillation and gives time for the operator to shift the stock being bent to a new position. This period of delay at extreme positions is further increased by the 100

pin and slot connection 50, 51 between the crank and the left end of the connecting rod (Fig. 1).

In order to feed the bar away from the machine after it is bent, a pair of metal rollers 52, 53 are provided, such rolls being mounted in a frame 54, the lower one of such rollers being driven. This roll 53 is provided with a gear 55 meshing with a driving pinion 56. The shaft 57 of the pinion 56 is driven from the pinions 58 and 59 and the gear 59 is provided with a sprocket 60 driven from the sprocket 61 by means of a chain 62. The sprocket 61 is mounted upon the end of the shaft 33 whose drive has already been described.

In starting the bending operation, the parts of the machine occupy the position shown in Fig. 1 with the slot 11 of the movable die in alignment with the slot 14 of the fixed die, and the end of the bar 12 is pushed through the slots until its end engages the stop block 63 (Fig. 1). The machine is then started, and the crank 42 moves the plate 8 carrying the movable die 9, 10 to the position shown in Fig. 2, thus giving the bar two bends, one of which is around the toe 17 of the fixed die and the other of which is around the toe 13 of the movable die. During this movement the slot 11 is kept parallel to the slot 14, due to the mounting of the plate 8 which carries the movable die, upon the parallel links 4 and 5. When this bending movement is completed, the cam 27 swings the arms 22 and 21 to lift the plate 18 which carries the fixed die upward a slight distance. This movement serves to free the fixed die from the bar, so that this bar, now partially bent, can be moved back by the movable die to the starting position of Fig. 1, preliminary to pushing the bar ahead until its last bend engages the stop 63. When the bar is back again at the position of Fig. 1, the cam 27 has rotated far enough to permit the plate and fixed die to move down so that the slot 14 fits over the bar. The rotation of the rolls 52 and 53 help to carry the bar ahead when it is released by the dies. While the bar is held against movement by the dies, the rolls slip over the bar, which they engage with only a slight amount of pressure. It will be observed that each movement of the dies produces two bends in the stock and that this is due to the fact that the movable die is moved so that its slot is maintained throughout its movement in parallelism with the slot of the fixed die. This double bending has the further advantage that it does not cause the bar to swing back and forth on a wide arc as is the case where the machine employed forms only a single bend at each operation, which arc increases as the length of bent stock increases.

The bending apparatus, as above described, will not make a sharp bend around

the toes 13 and 17, unless special provision is made to accomplish this result. This is easily accomplished with respect to the bend at 17, but involves more difficulty in bending sharply about the toe 13. To accomplish the result at the toe 17, a block 64 is provided upon the link 4 which engages the bar 12 on the side opposite to the toe 17. This block moves around with the link forcing the bar to bend sharply around the toe, and occupying the position shown in Fig. 2 at the end of the bending movement. To accomplish the desired result at the toe 13, the attachment shown in Figs. 5 and 6 is employed. This device is omitted from the other figures of the drawings in order to avoid confusion, but its location with respect to the body of the machine will be clear from inspection of such Figs. 5 and 6, which shows the movable dies and associated parts of the machine, and upon comparison with Fig. 4, which shows the plate and post carried by the movable die upon which the device is supported.

Secured upon the die member 10 by the three rivets 65 (Fig. 5), is a plate 66, which in turn carries a post 67 in vertical alignment with the pin 6. Slidably and rotatably mounted on the post is the block 68. This block has a depending finger 69, which lies against the bar 12 on the side thereof opposite to the bending toe 13 of the die and performs the same function in bending around this toe as is accomplished by the block 64 in bending around the toe 17 of the fixed die. The block 68 is caused to rotate about the post 67 in a counter clockwise direction as the movable die moves from the full line position of Figs. 1 and 5 to that of Fig. 2 and to the dotted line position of Fig. 5 by a radius arm 69^a mounted in a slot 70 through the top of the block and held by a plate 71. The other end of the arm 69^a is pivoted upon a bolt 71^a carried by a bracket 72 secured to the plate 18 which carries the fixed die. In moving from the full line position of Fig. 5 to the dotted line position of such figure, the finger 69 is kept against the bar 12, forcing it to bend sharply around the toe 13.

After the bar has been bent to the dotted line position of Fig. 5, it is necessary to move the finger 69 upward to release the bar 12 preliminary to moving the die back to starting position, and this is accomplished by the lever 72 pivoted upon the pin 73, and normally held in the horizontal position shown by the spring 74. When the parts have been moved to the dotted line position of Fig. 5, the end of the lever lies above the plate 18, so that when this plate is moved vertically to release the fixed die from the bar as heretofore explained, the lever is also lifted, sliding the block 68 upward on the pin 67 and moving the finger upward to release position

above the bar 12. The block 68 with its finger 69 is held in this elevated position during the movement of the die 9, 10 back to full line position, by a latch plate 75 pivoted for swinging movement at 76 and yieldingly pulled toward the post 67 by the spring 77. When the block 68 is slid upward on the post 67, as above described, the plate 75 moves over the shoulder 78 on the post, so that the block will be held in its upper release position until the plate is swung outward so that it moves off of the shoulder.

The release of the latch plate from the shoulder to permit the block 68 to move back to the position of Fig. 6, occurs when the parts return to the full line position of Fig. 5. The movement of the latch plate at this time is accomplished by a pin 79 extending through the post just above the shoulder 78. In moving from the dotted line position of Fig. 5 to the full line position, the relative movement between the pin and the latch plate is such as to cause the parts to assume the relation shown in full lines, at which time the pin pushes the latch plate off of the shoulder 78, allowing the block 68 to drop down by gravity to the position shown in Fig. 6.

The operation of the machine will be apparent from the foregoing description. With the parts in the position shown in Fig. 1, the bar or stock 12 to be bent is pushed up through the die slots 11 and 14 till its end engages the stop 63. The drive of the motor 29 operating through gearing described and the crank 42, then swings the plate 8 and movable die 9, 10 carried by the parallel links 4 and 5 up to the position of Fig. 2, thus bending the bar around the toes 17 and 13 of the two dies. The cam 27 operating through the arms 22 and 21 now swings the ribbed plate 18 carrying the fixed die upward to release it from the bent bar, and at the same time, the depending finger 69 carried by the block 68 is moved upward by the lever 72, whose end lies above the plate 18. This releases the bar 12 from the finger preliminary to moving the movable die and associated parts back to the position of Fig. 1, and such finger (and the block 68 which carries it) are held up in this position by the latch plate 75 until the parts reach the position of Fig. 5 when the plate is released from the shoulder 78 by the pin 79. The constantly rotating rolls 52 and 53 feed the bar 12 forward when it is released from the dies, as above described. With the machine parts again in the position of Fig. 1, the operator again positions the bar 12 in the die slots 11 and 14 with the rearmost bend of the stock against the stop 63 (Fig. 1) and the parts are again operated to give the bar another double bend. This operation is continued until the entire bar is bent.

It will be understood that the term slot as

employed in the specification and claims in connection with the dies is used in its broad sense as meaning any means for engaging the bar on its two sides and holding it during the bending operation. Further, while two dies each having a slot is the preferred construction, it is not absolutely necessary that each die should have a slot. The use of the slots insures a sharper bend than can be secured if a die merely has a bending nose, but in some cases sharp bends are not required or any part of the bends which are not made sharply enough may be made more abrupt by a supplemental bending device.

What I claim is:

1. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for swinging the movable die back and forth, and means whereby the die is caused to pause when in its two extreme positions.

2. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, a power driven crank for swinging the movable die back and forth, and lost motion connections intermediate the crank and die for causing the die to pause in its two extreme positions.

3. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for giving the movable die its swinging movement, and means for shifting the fixed die transversely of the plane of movement of the movable die at the end of the bending movement in order to release such fixed die from the bar and permit the bar to be moved forward preliminary to another bending operation.

4. In combination in a bar bending machine, two dies in alignment for receiving the bar to be bent and each having a slot with a bending toe at the end thereof, one of which dies is fixed, and the other mounted for

swinging movement about the fixed die as a center, means whereby the slot of the movable die is maintained in parallelism with that of the fixed die during the swinging movement of such movable die, power means for giving the movable die its swinging movement, a finger carried by the movable die and arranged to engage said bar in advance of the toe of the die on the side of the bar opposite to such toe, and means for rotating the finger about the toe of said movable die during the swinging movement thereof, causing the bar to make a relatively sharp bend around such toe.

5. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for giving the movable die its swinging movement, a finger carried by the movable die and arranged to engage said bar in advance of the toe of the die on the side of the bar opposite to such toe, and means for rotating the finger about the toe of such movable die during the swinging movement thereof, causing the bar to make a relatively sharp bend around such toe, said means comprising a radius arm pivoted at the center about which the movable die swings.

6. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for giving the movable die its swinging movement, a finger carried by the movable die and arranged to engage said bar in advance of the toe of the die on the side of the bar opposite to such toe, means for rotating the finger about the toe of such movable die during the swinging movement thereof so as to cause the bar to make a relatively sharp bend around such toe, and means for lifting the finger to release the bar when the movable die reaches its extreme bending position.

7. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging

movement of such movable die, power means for giving the movable die its swinging movement, a finger carried by the movable die and arranged to engage said bar in advance of the toe of the die on the side of the bar opposite to such toe, means for rotating the finger about the toe of such movable die during the swinging movement thereof so as to cause the bar to make a relatively sharp bend around such toe, means for lifting the finger to release the bar when the movable die reaches the extreme bending position, and means operated by the movement of the movable die back to starting position to cause the return of the finger to engaging or operative position.

8. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for giving the movable die its swinging movement, means for shifting the fixed die laterally at the end of the bending movement to release the bar from such fixed die, a finger carried by the movable die and arranged to engage said bar in advance of the toe of the die on the side of the bar opposite to such toe, means for rotating the finger about the toe of such movable die during the swinging movement thereof so as to cause the bar to make a relatively sharp bend around the toe, and means actuated by the lateral movement of the fixed die for lifting the finger to release the bar when the movable die reaches its extreme bending position.

9. In combination in a bar bending machine, two dies in alignment for receiving the bar to be bent and each having a slot with a bending toe at the end thereof, one of which dies is fixed, and the other mounted for swinging movement about the fixed die as a center, means whereby the slot of the movable die is maintained in parallelism with that of the fixed die during the swinging movement of such movable die, power means for giving the movable die its swinging movement, means for shifting the fixed die laterally at the end of the bending movement to release the bar from such fixed die, a finger carried by the movable die and arranged to engage said bar in advance of the toe of the die on the side of the bar opposite to such toe, means for rotating the finger about the toe of such movable die during the swinging movement thereof so as to cause the bar to make a relatively sharp bend around the toe, means actuated by the lateral movement of the fixed die for lifting the finger to release the bar when the movable die reaches its ex-

treme bending position, and means operated by the movement of the movable die back to starting position for releasing the finger so that it returns to its operative starting position.

In testimony whereof, I have hereunto subscribed my name this 21st day of November, 1929.

ROBERT L. HIBBARD.
